UNITED STATES PATENT OFFICE.

RASMUS M. HVID, OF CHICAGO, ILLINOIS, ASSIGNOR TO R. M. HVID COMPANY, OF CHICAGO, ILLINOIS, A CORPORATION OF MICHIGAN.

GOVERNOR CONTROL.

1,283,781.

Specification of Letters Patent.

Patented Nov. 5, 1918.

Application filed December 3, 1917. Serial No. 205,134.

To all whom it may concern:

Be it known that I, RASMUS M. HVID, a citizen of the United States, and resident of Chicago, in the county of Cook and State 5 of Illinois, have invented certain new and useful Improvements in Governor Controls, of which the following is a specification.

My invention relates to governors particularly adapted for use in connection with 10 internal combustion engines.

An object of the invention is to provide combined manual and governor controlled fuel feeding mechanism so arranged that manual control throughout the entire range 15 of fuel feeding is possible but in which it is impossible for the operator to fail to perform any steps which would have the effect of operatively disconnecting the engine from its governor control when the manual control is released. This is an important point. It is common to adjust the governor in such 20 manner that the engine will run at a certain predetermined speed but it frequently becomes necessary, momentarily, to decrease 25 or increase such predetermined speed. I am aware that in the constructions heretofore proposed it has been possible to so disconnect the governor from the throttle or speed regulating means that this may be 30 accomplished. However, there is in such constructions the danger that the operator may neglect to re-establish the governor control and the engine may be injured and great damage done by racing. To avoid 35 this difficulty and assure governor control irrespective of the volition of the operator, I have provided an extremely simple mechanism so arranged that the manual control of the fuel valve may be effected throughout 40 its entire range but which will automatically be re-connected when the manual control is released.

The invention will be more readily understood by reference to the accompanying 45 drawings, wherein,

Figure 1 is an elevation of a construction such as contemplated by me, the governor being shown diagrammatically,

Fig. 2 is a view taken at right angles to 50 that of Fig. 1, and

Fig. 3 is a fragmentary detail, the view being taken on the line 3-3 of Fig. 2.

In the drawings the engine is indicated at 10, the fuel valve stem 11, being threaded

and adapted for rotation to increase or 55 lessen the amount of fuel supplied by means of the reciprocating rod 12. The rod is suitably connected to the upper end of a lever or crank 13, which is mounted for freedom of rotation on a shaft 14. The crank is 60 provided with a projection or handle 15, at one side and a pin 16, at the other side.

The governor, indicated diagrammatically at 17, may be of any approved type. The fly-ball governor shown is adapted to 65 engage one arm 18, of a bell-crank, also mounted on the shaft 14, the other arm 19, of the bell-crank being provided at its upper end with a hook formed partly by the curved portion 20, and partly by the leaf-spring 70 21. The hook thus formed is adapted to resiliently engage the pin 16. It will be noted that the rigid portion 20, abuts and lies at one side of the pin 16, that is, in such manner that the fuel valve rod 12, is positively moved toward a reduced speed position. When the rod is to be moved in the opposite direction the engagement is effected by the frictional contact of the leaf-spring 75 with the pin. In operation the bell-crank 80 or equivalent structure, is oscillated by the vertical reciprocation of the governor under the action of the fly-balls.

By means of the handle or knob 15, the operator may disengage the fuel control 85 members from the governor lever to secure speeds lower than that fixed by the governor. If he wishes to secure higher speeds he must do so by overcoming the force exerted by the governor. In whatever position the fuel control lever is placed by the operator, it will be engaged by the governor lever upon any increase in speed of the engine. If the operator leaves the two levers in disengaged position and the speed of the 95 engine should increase, the governor lever will move up to and engage the pin 16, of the manual control lever and thereafter the control will be effected solely by the governor. 100

The manner of mounting the levers is unimportant. It is only necessary that the path or arc of movement of the manual control and governor levers should intersect in order that it be impossible for the operator to disengage the governor and prevent its control at higher speeds than those determined by the governor setting. Modifica- 105

tions in this and other features are considered to be within the scope of my invention.

I claim:

- 3 1. In a hydrocarbon engine, the combination with a cylinder having a fuel valve, of means for controlling the position of said valve, said means including a governor, an arm operated thereby, a manual control arm 10 connected to said fuel valve, said governor arm abutting and being adapted to be resiliently and removably connected to the manual control arm, the form of connection being such as to permit manual control 15 dependent of the governor for speeds lower than permitted by the governor, substantially as described.
2. In a hydrocarbon engine, the combination of a fuel control member, means for 20 manually moving said member, a governor, and means for resiliently uniting the fuel control and governor elements the resilient connection permitting disengagement of the fuel control member from the governor and 25 permitting independent manual fuel control at points below the speed limit established by the governor, said resilient connection being such as to automatically effect the uniting of the fuel control and governor elements when said elements come into contact, 30 substantially as described.

3. In a hydrocarbon engine, the combination of a cylinder having a fuel valve, a lever for controlling the position of said valve, a governor, a lever operated thereby, manual control means positively connected to said fuel control valve, said governor lever abutting said manual control means, and means for removably connecting the governor lever, and manual control means to permit 35 of disconnection, and manual control for lower speeds than permitted by the governor, substantially as described.

4. In a hydrocarbon engine, the combination of a cylinder, a liquid fuel valve, a reciprocating rod for controlling said valve, a lever connected to the rod and adapted for manual oscillation, a governor, a lever adapted to be oscillated thereby, said manual and governor levers being mounted for 50 oscillation in intersecting arcs, means for preventing the movement of the manual lever past the governor lever and for permitting the movement of the manual lever away from the governor lever and toward closed 55 position of said valve, substantially as described.

Signed at Chicago, Ill., this 30th day of November, 1917.

RASMUS M. HVID.
